UNITED STATES PATENT OFFICE.

NATHAN ALLEN GIBBONS, OF MARTINS FERRY, OHIO, ASSIGNOR TO WHITAKER-
GLESSNER COMPANY, OF WHEELING, WEST VIRGINIA, A CORPORATION OF WEST
VIRGINIA.

KNOCKDOWN BARREL.

Application filed March 8, 1922. Serial No. 541,912.

To all whom it may concern:

Be it known that I, NATHAN ALLEN GIBBONS, a citizen of the United States of America, and resident of Martins Ferry, county of

5 Belmont, and State of Ohio, have invented certain new and useful Improvements in Knockdown Barrels, of which the following is a specification.

This invention relates broadly to metallic barrels and similar containers, and more particularly to a barrel of collapsible, or knock-down, type.

The primary object of the invention is to provide a simple, inexpensive and improved form of knock-down metallic barrel, the same being conveniently set up and taken apart as occasion requires and, when set up and closed, possessing great rigidity and strength.

20 A further object is to provide a barrel embodying staves of light sheet metal and having a detachable head and chime structure whereby said staves are supported and reinforced to the extent that they are maintained 25 rigidly against collapse.

With this and other objects in view, the invention resides in the features of construction, arrangement of parts and combinations of elements which will hereinafter be described, reference being had to the accompanying drawings, in which—

Figure 1 is a perspective view of a barrel embodying my invention;

Figure 2 is a central vertical section of the 35 same;

Figure 3 is a central horizontal section of the same;

Figure 4 is a perspective view of the chime;

40 Figure 5 is a perspective view of a stave;

Figure 6 is an enlarged detail section of a fragmentary portion of an end of the barrel with the head and chime in place;

Figure 7 is a plan view of the metal blank 45 from which the stave shown in Fig. 5 is formed;

Figure 8 is a perspective view of a modified form of stave;

Figure 9 is a plan view of the blank from 50 which said modified stave is formed;

Figure 10 is an end view of the stave shown in Fig. 8;

Figure 11 is a section on line 11—11, Fig. 8; and—

Figure 12 is an enlarged section on line 12—12, Fig. 1.

Referring to said drawings, the body of the barrel is shown as composed of a plurality of staves 1, each of which is tapered slightly from its middle toward its opposite ends to provide for the usual bulge when fitted with others into barrel form. Each of said staves 1 is formed from a sheet-metal blank having the approximate shape shown in Fig. 7 in which the lateral edges 2 of the body 3 have a slight convex curvature extending from end to end thereof, and integral tongues 4 of suitable reduced width extend from the central portions of the opposite ends of said body.

In the formation of the stave 1, the said lateral edges 2 of the blank are turned or bent outward and inward to form hook like flanges 5. Thus, when two staves are placed in abutting relation, as shown in Figs. 3 and 12, the adjacent flanges or hooks 5 thereof are adapted to receive in interlocking relation thereto the opposite or reversely directed hooks 6^a of locking strips 6, said strips having a length corresponding to that of 80 said hooks 5 and being slidable lengthwise along said hooks into and out of interlocking position.

The reduced tongues 4 have small outwardly pressed horizontal beads 7 formed 85 therein at points substantially midway of their lengths, and the channel formed interiorly of the tongue in the production of said bead is designed to align with the channels of tongues of other staves employed in 90 the formation of the barrel, whereby is constituted a substantially continuous internal annular channel at each end of the barrel. Said channel is designed for the reception of an external annular bead 8 pressed in the 95 upright annular flange 9 of a head 10 whereby the end of the barrel is closed. Due to the flexibility of the tongues 4, the latter may be readily forced outward sufficiently to permit of introduction of the head or closure 100 10 to a level at which the bead 8 is received in said annular channel. Following the introduction of the head, a reinforcing clamp or chime 11 is fitted into embracing relation

to the tongues 4 and head flange 9, said chime being of saddle shape and having a plain vertical inner member 11^a designed to closely seat against the internal face of 5 the flange 9 and having the outer member 11^b thereof designed to closely embrace the various tongues 4 for holding the latter firmly against said head flange, said outer member having a channel 12 pressed therein 10 for the reception of the beads 7 of said tongues.

The chime 11 is of split ring form, as shown in Figs. 1 and 4. One of the ends of said ring or chime has the inner member 15 11^a thereof prolonged to form a tongue 13 which, when said chime is seated in place, projects between the members 11^a and 11^b of the opposite end and has a bolt hole 14 provided therein located in register with 20 similar holes 15 provided in alined relation in said members. A small stove bolt 16 introduced through the alined holes will not only retain the chime ends in closed relation, but will also cooperate with 25 one or more additional suitable located bolts 17 for retaining said chime and the head 10 in their seated positions. Said bolts 17, as also the bolt 16, are also directed through holes 18 and 19 provided, 30 respectively, in the intermediate head-flange 9 and stave-tongue 4, as is shown in Fig. 6.

In the formation of the modified stave shown in Figs. 8, 10 and 11, a straight edged blank body 3^a is employed, and the end portions of said blank are rendered slightly tapered in form by the provision of suitably formed corrugations 20 extending from the opposite ends of the stave to points near the midlength of the latter. These corrugations 40 are turned over and flattened in the form of crimps 21 in the tongue portions 4^a of the stave, somewhat in the manner shown in Fig. 10.

What is claimed is—

45 1. A sheet-metal barrel comprising staves having lateral outwardly turned hook-like flanges, locking strips having lateral in-turned flanges interlocking the flanges of adjacent staves, said strips being slidable lengthwise into and out of interlocking relation to said stave-flanges, each stave having its end reduced in width and prolonged to form a tongue and the tongues of said staves having horizontal outwardly pressed beads 50 formed therein whereby is constituted an internal annular channel, a head having an upright annular flange fitted closely within the embrace of said tongues, said flange having an outwardly pressed bead for seating in said channel, a saddle-like chime fitted over and embracing said tongues and the head flange, the outer member of 55 said chime being channeled interiorly to conformably fit upon the beads of said tongues, said chime being of split-ring form and having a tongue at one end thereof for fitting between the inner and outer members of the opposite end thereof, and detachable means for securing said chime in its seated position.

60 2. A sheet-metal barrel comprising staves having lateral outwardly turned hook-like flanges, locking strips having lateral in-turned flanges interlocking the flanges of adjacent staves, said strips being slidable lengthwise into and out of interlocking relation to said stave-flanges, each stave having its end reduced in width and prolonged to form a tongue and the tongues of said staves having horizontal outwardly pressed beads 65 formed therein whereby is constituted an internal annular channel, a head having an upright annular flange fitted closely within the embrace of said tongues, said flange having an outwardly pressed bead for seating in 70 said channel, a saddle-like chime fitted over and embracing said tongues and the head flanges, the outer member of said chime being channeled interiorly to conformably fit upon the beads of said tongues, said chime 75 being of split-ring form and having a tongue at one end thereof for fitting between the inner and outer members of the opposite end thereof, and detachable means for securing said chime in its seated position.

80 3. A sheet-metal barrel comprising staves having lateral outwardly turned hook-like flanges, locking strips having lateral in-turned flanges interlocking the flanges of adjacent staves, said strips being slidable lengthwise into and out of interlocking relation to said stave-flanges, each stave having its end reduced in width and prolonged to form a tongue and the tongues of said staves having horizontal outwardly pressed beads 85 formed therein whereby is constituted an internal annular channel, a head having an upright annular flange fitted closely within the embrace of said tongues, said flange having an outwardly pressed bead for seating in 90 said channel, a saddle-like chime fitted over and embracing said tongues and the head flanges, the outer member of said chime being channeled interiorly to conformably fit upon the beads of said tongues, said chime 95 being of split-ring form and having a tongue at one end thereof for fitting between the inner and outer members of the opposite end thereof, and detachable means for securing said chime in its seated position.

100 4. A sheet-metal barrel comprising staves having lateral outwardly turned hook-like flanges, locking strips having lateral in-turned flanges interlocking the flanges of adjacent staves, said strips being slidable lengthwise into and out of interlocking relation to said stave-flanges, each stave having its end reduced in width and prolonged to form a tongue and the tongues of said staves having horizontal outwardly pressed beads 105 formed therein whereby is constituted an internal annular channel, a head having an upright annular flange fitted closely within the embrace of said tongues, said flange having an outwardly pressed bead for seating in said channel, a saddle-like chime fitted over and embracing said tongues and the head flange, the outer member of 110 said chime being channeled interiorly to conformably fit upon the beads of said tongues, said chime being of split-ring form and having a tongue at one end thereof for fitting between the inner and outer members of the opposite end thereof, and removable bolts directed through said chime and the 115 intermediate portions of said stave tongues and said head flange.

In testimony whereof, I affix my signature in presence of two subscribing witnesses.

NATHAN ALLEN GIBBONS.
